(57) **CLAIM**

The ornamental design for a detector for metallic bodies and objects, as shown and described.

DESCRIPTION

The patent or application file contains at least one drawing executed in color. Copies of this patent or patent application publication with color drawing(s) will be provided by the Office upon request and payment of the necessary fee.

1. Detector for metallic bodies and objects

1.1 : Perspective

1.2 : Front

1.3 : Left

1.4 : Top

1.1 Perspective front view; 1.2 front view; 1.3 side view; 1.4 top view.

The elements of the design lined in red form no part of the claimed design.

1 Claim, 4 Drawing Sheets
(4 of 4 Drawing Sheet(s) Filed in Color)
